UNITED STATES PATENT OFFICE

157,670

PIN REMOVING PUNCH PLIERS

John J. Greco and Irving M. Neitlich, Brooklyn,
N. Y., assignors to Greco Mfg. Corp., Brooklyn,
N. Y.

Application February 19, 1949, Serial No. 952

Term of patent 14 years

(Cl. D54—13)

To all whom it may concern:

Be it known that we, John J. Greco and Irving M. Neitlich, both citizens of the United States, both residing at Brooklyn, New York, in the county of Kings and State of New York, have invented a new, original, and ornamental Design for a Pin Removing Punch Pliers, of which the following is a specification, reference being had to the accompanying drawing, forming a part thereof.

In the drawing:

Fig. 1 is a front perspective view of a pin removing punch pliers, showing our new design; and

Fig. 2 is a rear perspective view of the same.

We claim:

The ornamental design for a pin removing punch pliers, as shown.

JOHN J. GRECO.
IRVING M. NEITLICH.
